(57) **CLAIM**

The ornamental design for a rear luggage face, as shown and described.

DESCRIPTION

FIG. 1 is a perspective view of a rear luggage face showing my new design;

FIG. 2 is a front elevational view thereof;

FIG. 3 is a left side elevational view thereof;

FIG. 4 is a right side elevational view thereof; and,

FIG. 5 is a top plan view thereof.

The broken lines showing of luggage is for illustrative purpose only and forms no part of the claimed design.
